UNITED STATES PATENT OFFICE.

WILLIAM S. ELDER, OF PHILADELPHIA, PENNSYLVANIA, ASSIGNOR TO JULIUS HIRSH, OF PHILADELPHIA, PENNSYLVANIA.

UNDERGARMENT.

1,083,069.

Specification of Letters Patent. Patented Dec. 30, 1913.

Application filed February 21, 1913. Serial No. 749,862.

To all whom it may concern:

Be it known that I, WILLIAM S. ELDER, a citizen of the United States, residing in Philadelphia, Pennsylvania, have invented 5 certain Improvements in Undergarments, of which the following is a specification.

My invention relates to that type of knitted undergarment which is provided with overlapping crotch flaps both at front and 10 rear, the object of my invention being to so construct such a garment as to prevent objectionable horizontal seams at the waist portion, the flaps being, by preference, so formed as to permit of the cutting of the 15 garment from a tube of knitted fabric without material waste.

In the accompanying drawing Figure 1 is a view of one form of union suit made in accordance with my invention; Figs. 2 and 20 3 are respectively front and back views of another form of the suit; Fig. 4 is a view of a pair of drawers embodying the invention; Fig. 5 is a view illustrating the method of cutting a tube of knitted fabric for the 25 production of the garment shown in Fig. 1; Fig. 6 is a view showing the method of cutting the tube of knitted web for the production of the garment shown in Figs. 2 and 3, and Fig. 7 is a view showing the method of 30 cutting the web for the production of the garment shown in Fig. 4.

The body portion of each of the garments shown in Figs. 1, 2 and 3 of the drawing is composed of right and left hand members 35 1 and 1^a, of similar construction, these members being united at the front and back of the garment, either by buttons and button-holes at the front, as shown in Fig. 2, and by a central vertical seam 2 extending from 40 waist to neck at the rear, as shown in Figs. 1 and 3, or by seams at both front and rear in a garment of the character shown in Fig. 1. The leg members 3 and 3^a and hip members 4 and 4^a of each garment constitute integral 45 continuations of the body members 1 and 1^a respectively, and between the crotch portion of the garment, where the leg members meet, and the waist portion of the garment, where the buttoned front and the back 50 seam 2 terminate, the hip members 4 and 4^a of the garment are provided with overlapping flaps 5, these overlapping flaps being alike both in front and rear, the overlap

of the flaps diminishing toward the top, and the upper end of each flap terminating at 55 the lower end of the buttoned front or front seam of the garment or at the lower end of the rear seam 2. By this means the formation of horizontal seams at front and rear of the garment adjacent to the waist line is 60 prevented and the annoyance to the wearer due to the presence of such seams is overcome. This method of forming the flaps 5 also conduces to the cutting of the garments without material waste, as hereinafter ex- 65 plained.

The garment shown in Fig. 1 is a low-necked sleeveless, union suit having short legs of the full width of the knitted tube from which the garment is cut. The garment 70 shown in Figs. 2 and 3 is a high-necked union suit having shaped legs of ankle length and also provided with sleeves, although it may be sleeveless if desired. The garment shown in Fig. 4 is a pair of draw- 75 ers having shaped legs of ankle length and also having hip portions provided with front and rear crotch flaps 5 similar to those shown in Figs. 1 and 2, the body portion of this garment being reduced to a relatively 80 narrow strip at the waist.

The garment shown in Fig. 1 can be cut from a tube of knitted web in the manner shown in Fig. 5 by forming therein a central incision 6, and at each end of the same 85 a diagonally directed incision 7, that at one end being on one side of the central incision and that at the other end on the opposite side of the same. By this means the flaps 5 are formed from that portion of the web 90 which is cut out to form the low neck, the arm holes being formed by short vertical incisions 8 at opposite sides of the web.

In cutting the garments shown in Figs. 2, 3 and 4 the methods shown in Figs. 6 and 95 7 are adopted, the surplus portions 9 shown by the dotted line being available for the formation of gussets for use in various portions of knitted undergarments.

Each of the methods described of cutting, 100 while preventing waste, also provides the wide hip portions required in garments intended for women's wear.

Although the flaps 5 extend for a considerable distance above the actual crotch of 105 the garment they have become known to the

trade as "crotch flaps" and this term has therefore been used in describing them.

I claim:

5 A knitted undergarment consisting of opposite halves, each comprising a body member, a leg member and a hip member, with overlapping crotch flaps at front and rear, two of said crotch flaps being integral with one hip member and the other two being integral with the other hip member, the body

members being united centrally at the front and rear of the garment and the crotch flaps being the same both at front and rear.

In testimony whereof, I have signed my name to this specification, in the presence of 15 two subscribing witnesses.

WILLIAM S. ELDER.
